LOCK FOR LUGGAGE CASES AND OTHER CONTAINERS

Abraham Levine, Elizabeth, N. J.

Application February 9, 1939, Serial No. 255,409

4 Claims. (Cl. 70—73)

This invention relates to improvements in hasp lock mechanism for luggage cases and other types of containers.

The invention has for an object to provide a hasp lock mechanism comprising manipulatable latching means for cooperation with the loop of a hasp device, said latching means being mounted for both sliding and pivotal movements under control of a single spring means, whereby said spring means is adapted to yieldably thrust said latching means into engaged relation to the loop of said hasp device, and also to yieldably retain said latching means in selected positions to which it may be pivotally moved and wherein the same, in one said position, is free for longitudinal movement relative to the hasp device, but in another of said positions is locked against longitudinal manipulation and movement, and thus against disengagement from holding relation to the hasp loop.

The invention has for another object to provide in a hasp lock mechanism, having spring controlled latching means subject to longitudinal and pivotal movements as and for the purposes above mentioned, in connection with which novel key engageable means is provided for moving the same to and from selected pivotally swung positions.

The invention has for another object to provide a hasp lock mechanism of the kind mentioned, wherein the latching means and its control spring is supported by a carrying frame adapted to be mounted within and in turn operatively position and support these parts within a suitable housing or casing.

Another object of this invention is to provide in a hasp lock mechanism, a novel form and construction of hasp element and means for mounting the same so that it is self-withdrawing from the associated locking means when released from the restraint of the latching means possessed by the latter.

Other objects of this invention, not at this time more particularly enumerated, will be understood from the following detailed description of the same.

Illustrative embodiments of this invention are shown in the accompanying drawings, in which:

Fig. 1 is an exterior face view of one form of hasp lock mechanism according to this invention, and Fig. 2 is a side elevational view thereof.

Fig. 3 is a vertical longitudinal section, taken on line 3—3 in Fig. 1, but drawn on an enlarged scale; Fig. 4 is a transverse sectional view,

taken on line 4—4 in Fig. 3; Fig. 5 is a view similar to that of Fig. 4, but showing the latching means moved to released position relative to the loop of the hasp device; Fig. 6 is a view similar to that of Fig. 3, but with the hasp device released; Fig. 7 is a view similar to that of Figs. 4 and 5, but showing the latching means pivotally moved by an inserted actuating key to a position wherein it is locked against longitudinal hasp releasing movement; and Fig. 8 is a horizontal section, taken on line 8—8 in Fig. 3.

Fig. 9 is an exterior face view and Fig. 10 a side elevation of a somewhat modified form of hasp lock mechanism according to this invention.

Fig. 11 is a sectional view, taken on line 11—11 in Fig. 10, the housing or external casing being omitted; Fig. 12 is a view similar to that of Fig. 11, but showing the hasp latching means released relative to the hasp loop; Fig. 13 is a horizontal section, taken on line 13—13 in Fig. 20 11; and Fig. 14 is a view similar to that of Fig. 11, but showing the latching means pivotally moved by an inserted actuating key to a position wherein it is locked against longitudinal hasp releasing movement.

Similar characters of reference are employed in the hereinabove described views, to indicate corresponding parts.

Referring to Figs. 1 to 8 inclusive, the form of the novel hasp lock mechanism therein illustrated comprises an external housing or casing 1 adapted to be affixed by suitable fastening means, such, e. g., as rivets 2, to the body section 3 of a luggage case or other container. The housing or casing 1 is provided in its face wall 35 with a suitably located access opening 4 through which the loop 5 of a hasp element 6 may enter. Said housing or casing 1 is also provided with a suitably located key hole 7 through which a key may be passed and thereupon manipulated 40 to lock or release the latching means contained within the housing or casing. The reference character 8 indicates the hasp mounting casing adapted to be affixed by suitable fastening means, such, e. g., as rivets 9, to the cover section 10 of 45 the luggage case or other container.

Fixed within the housing or casing 1 is a carrying frame for supporting the hasp latching means of the lock mechanism. Said carrying frame comprises a body plate 11 having along 50 and integral with its longitudinal margins side flanges 12 approximating in projectional extent the thickness of a latching means to be supported. Said body plate 11 is suitably fixed within the housing or casing 1 with its side flanges 55

12 directed toward and abutting the front wall of said housing or casing. Mounted for movement within the space intermediate the front wall of the housing or casing 1 and the body plate 11 of the carrying frame is a latching means comprising a plate-like body 13 having at one end an extension 14 of considerably reduced width. Said extension 14 projects exteriorly through an opening 15 provided in an end wall 10 of the housing or casing, and the rounded extremity 16 of said extension constitutes an external finger-piece for purposes hereinafter explained. Formed in the extension 14 is a longitudinal slot 17, the inner end of which forms 15 a rounded bearing portion 18. Said frame body plate 11 is cut away at one end to form a fulcrum post 19 suitably located to extend through said slot 17, and suitably rounded on its inner face to correspond to and fit the bearing portion 20 18, thus pivoting the body 13 of the latching means for lateral swinging movement. Said latching means body 13 is of tapering width from its pivoted end toward its opposite or free end, thus permitting desired play or lateral swinging 25 movements thereof. Projecting from the free end of said body 13, at a suitable point intermediate its sides, is a nosing 20. Also provided adjacent to the free end of said body 13 is a stop shoulder 21, which is preferably formed by 30 cutting away a corner portion of said body. This stop shoulder 21 is disposed for cooperation with a stop-lug 22 which is struck out of the frame body plate 11. Pivotal swinging movement of said latching body 13 in one direction will bring 35 said stop shoulder 21 in opposition to said stop-lug 22, and in the opposite direction will dispose said stop shoulder out of alignment with said stop-lug so that the former will clear the latter for permitted longitudinal movement of 40 said latching body 13. Means are provided for effecting by an inserted key K desired pivotal swing movements of said latching body 13, and to such end a portion of the latter is cut away 45 to provide a key clearance opening 23. One margin of said opening 23 is suitably indented to form properly spaced key bit engageable shoulders 24 and 25. The frame body plate 11 is provided with a key fulcruming pin 26 which extends into the key clearance opening 23 and 50 so as to be aligned with key hole 7 of the housing or casing 1.

Formed in the latching body 13 in a position to correspond to the location of the hasp loop access opening 4 of the housing or casing 1, is an opening 27 through which the hasp loop 5 may extend when entered in the housing or casing 1. Formed in connection with the latching body 13, to project into the opening 27 from the margin thereof toward the free end of said body 13, is a latch element 28. Said latch element 28 is provided at its free end with a chamfered face 29 directed toward the hasp loop access opening 4.

The frame body plate 11, at the end portion thereof which lies adjacent to the free end of said latching body 13, is provided with a transverse end flange 30 disposed to project toward and preferably so as to abut the front wall of the housing or casing 1; said flange 30 also being spaced somewhat away from the free end of said latching body 13. Interposed between said flange 30 and said free end of the latching body 13 is a spring means for controlling the movements of the latter. This spring means is of substantially U-shape, one leg 31 being disposed contiguous to said flange 30 so as to be supported

or purchased thereby. The other leg 32 of said spring means is provided with a nosing 33. Said spring means exerts a tensional endwise outward thrust upon the latching body 13 which causes the bearing portion 18 to bear upon the fulcrum post 19, thus stopping the latching body 13 in position to dispose the latch element 28 for hasp loop engagement; at the same time said spring nosing 33 engages one or the other side (as the case may be) of said latching body nosing 29, thereby to yieldingly hold the latching body 13 in a desired laterally swung position. 5 10

When the latching body 13 occupies an upwardly swung position (as viewed in Figs. 4 and 5), the stop shoulder 21 thereof is disposed out of alignment with said stop-lug 22 and so as to pass the latch when the latching body 13 is inwardly moved. Under these circumstances, the hasp loop 5, if entered through the access opening 4, will engage the chamfered face 29 of the latch element 28 so as to snap past the latter and thereupon be engaged in interlatched relation thereto (see Fig. 4). If it is desired to release the hasp loop 5 from such engagement, the operator merely pushes inwardly upon the finger piece 16, thus moving the latching body 13 longitudinally inward against the tension of the spring 31-32 (see Fig. 5). If it is desired to secure the latching body 13 against hasp-loop releasing movement, a key K is inserted through key-hole 7 and fulcrumed on pin 26. By turning the key clockwise, a bit thereof is moved into engagement with the shoulder 25, thus exerting a downward swinging pressure upon the latching body 13, whereby the latter is turned about the fulcrum post 19 so as to carry its stop shoulder 21 into opposition to the stop lug 22, whereby manipulated inward longitudinal movement of the latching body 13 is obstructed (see Fig. 7). To again release the latching body 13 for longitudinal manipulation, the key K is inserted and turned anti-clockwise, to carry its bit into lifting engagement with the shoulder 24, whereby said latching body 13 is swung upward to normal initial position shown in Fig. 4.

In Figs. 1 to 4 and 6, there is shown a novel construction and arrangement of hasp element and mounting therefor. The body of the hasp element 6 terminates at its upper end in an angular extension 34 doubled back or rearwardly upon itself. Said angular extension 34 is entered downwardly through an opening 35 in the top wall of the casing 8, thus pivoting the hasp element upon a free margin 36 of the casing front wall which borders said opening 35 by engaging the internal juncture 37 of the hasp element and its angular extension thereon. Supported by lugs 38, with which the casing 8 is provided, is a bridging spring plate 39 formed to provide a flexible spring bar 40 which extends across and yieldably engages the lower free end of the angular extension 34 of the hasp element, thus operating to rock the latter to swing its body outward when unrestrained as to such movement (see Fig. 6). In order to retain the hasp element against lateral displacement or wobbling, its angular extension 34 is provided with a slot 41, and extending from the front wall of the casing 8 is a curved guide tongue 42 disposed to engage through said slot 41. 70

In Figs. 9 to 14 inclusive of the drawings, there is shown a somewhat modified form of hasp lock means, which embodies however the general principles of this invention. In this arrangement as shown, the reference character 50 indicates

cates the external casing or housing within which is suitably affixed a carrying frame 51 having the side flanges 52 for spacing the same relative to the front wall of said casing and housing, and modified at one or its forward end to provide a perforate end piece 53 to lie contiguous to the casing front wall, with its opening 54 aligned with a hasp loop access opening 55 with which the casing front wall is provided. At its rearward end said frame 51 is provided with a transverse end flange 56. Mounted between said frame 51 and the casing front wall is a longitudinally movable latching body 57 having a latch element 58 projecting from its forward end. 5

15 Pivotedly mounted on said latching body 57, by a pivoting rivet 59 or the like, is a laterally swingable member 60, the body of which is suitably cut away to provide a clearance opening 61, one margin of which is formed to provide key engageable shoulders 62 and 63. Slidable on the outer face of the casing front wall is a finger piece 64 connected by coupling tongues 65 with the latching body 57, said coupling tongues 65 extending through the clearance opening 61 so as not to 10

20 impede the lateral swinging movements of the member 60. At its rearward free end said swingable member 60 is provided with a suitably located nosing 66, and is further provided at its bottom edge adjacent to its free end, with a 25

25 stop tongue 67, adapted to cooperate, at proper times, with a receiving stop slot 68 formed in an adjacent side flange of the frame 51. Interposed between said flange 56 and the free end of said swingable member 60 is a U-shaped 30

30 spring means, one leg 69 of which is supported against said flange 56 and the other leg 70 of which thrust against the end of said swingable member 60. Said spring leg 70 is provided with a nosing 71 to cooperate with the nosing 66 of the 35

35 swingable member 60.

When the swingable member 60 occupies an upwardly swung position (as viewed in Figs. 11 and 12), the stop tongue 67 will be withdrawn out of the stop slot 68, thus freeing the latching body 57 for operative longitudinal movements. 40

45 Under these circumstances, the loop 72 of a hasp element 73, if entered through the access opening 55 of casing 50, will engage the chamfered end 58' of the latch element 58 carried by the latching body 57 so as to snap past said latch element 8 and thereupon be engaged in interlocked relation thereto (see Figs. 11 and 13). If it is desired to release the hasp loop 72 from such engagement, the operator merely pushes to the right the finger-piece 64, thus moving the latching body 57 longitudinally inward against the tension of the spring 69—70 (see Fig. 12). If it is desired to secure the latching body 57 against hasp loop releasing movement, a key K' is inserted through a key-hole 74 (in this case provided in the finger-piece 64) and thereupon turned clockwise to down-swinging engagement with the shoulder 63, thus swinging down the member 60 to carry its stop tongue 67 into the stop slot 68, whereby manipulated inward longitudinal movement of the latching body 57 is obstructed (see Fig. 14). To again release the latching body 57 for longitudinal manipulation, the key K' is turned in anti-clockwise direction to upswinging 50

55 engagement with the shoulder 62, whereby said member 60 is upswung to normal initial position wherein the stop tongue 67 is withdrawn from the stop slot 68, thereby again freeing the latching body 57 for longitudinal movement and manipulation. It will be obvious, that in the de-

scribed modified construction, the latching means is merely divided into two parts pivotally connected together and so mounted, that one part is arranged for longitudinal movement and the other for lateral swinging movements, all under the control of a single spring. It will thus be seen that functionally the modified arrangement is substantially similar to the first described construction, although for simplicity of structure, and from the standpoint of economy of material and production costs, the first described form is preferable. 10

I am aware that many changes could be made in the above described structures, as well as in the details of the construction of the same, without departing from the scope of my invention as defined by the appended claims. Hence, I do not limit my invention to the exact arrangements and combinations of the devices and parts as set forth in the foregoing specification, nor 20 do I confine myself to the exact details of the construction of said parts as illustrated in the accompanying drawings. 15

I claim:

1. In a hasp lock device including a pivoted hasp having a latching loop, a housing into which the hasp loop may be entered, a hasp loop latching means supported within said housing so as to be capable of both longitudinal and pivotal movements, a single spring means for controlling both longitudinal and pivotal movements of said latching means, cooperative stop means operative when said latching means is pivotally moved in one direction to obstruct longitudinal hasp loop releasing movement thereof, said latching means having key engageable means whereby the same may be pivotally moved by an inserted and turned actuating key, and said latching means having means exteriorly of said housing for manually moving the same longitudinally against the tension of said spring means. 30

2. In a hasp lock device including a pivoted hasp having a latching loop, a housing into which said hasp loop may be entered, a hasp loop latching means supported within said housing so as to be capable of both longitudinal and pivotal movements, said latching means having at its free end a projected nosing, a U-shaped spring the tensionally movable leg of which is provided with a nosing cooperative with said latching means nosing to determine the respective pivotally moved positions of said latching means, said latching means having a latch tongue to engage said hasp loop, said spring being adapted to yieldably thrust said latching means longitudinally in a direction to engage said latch tongue with said hasp loop, cooperative stop means operative when said latching means is pivotally moved in one direction to obstruct longitudinal movement of the same in a direction to release said latch tongue from said hasp loop, and said latching means having means exteriorly of said housing for manually moving the same longitudinally against said spring tension. 45

3. In a hasp lock device including a pivoted hasp having a latching loop, a housing into which the latching loop may be entered, a latching body, means for supporting said latching body within said housing for both longitudinal and pivotal movement, said latching body having a latch tongue to engage said hasp loop, spring means to yieldably retain said latching body in selected pivotally disposed position and in longitudinally moved position to engage its latch tongue with said hasp loop, means connected 50

55

60

65

70

75

- with said latching body exposed exteriorly of said casing for manipulating the same for longitudinal hasp loop releasing movement, cooperative stop means operative when said latching body is disposed in a selected pivotally moved position to obstruct longitudinal hasp loop releasing movement thereof, and key engageable means for producing desired pivotal movements of said latching body.
4. In a hasp lock device including a pivotal hasp having a latching loop, a housing into which the hasp loop may be entered, a frame means fixed within said housing, a latching body mounted between the housing front wall and said frame means for both longitudinal and lateral movements, cooperative means between said frame means and latching body to fulcrum the

latter for lateral movements, spring means purchased by said frame means to yieldably thrust said latching body to hasp loop latching position, said latching body having means exteriorly of said housing for longitudinally moving the same to hasp loop releasing position, said latching body having key engageable means for controlling its lateral movements, cooperative stop means adapted to be engaged when said latching body is moved to one lateral position and to be disengaged when the same is moved to its other lateral position, and said latching body and spring means having cooperating elements to yieldably retain the former in selected laterally moved position.

ABRAHAM LEVINE. 15
